O. WEIK

CONTAINER

Filed Feb. 9, 1928

FIG. 3.

Inventor
Oscar Weik

By, Eugene E. Steveng
Attorney

UNITED STATES PATENT OFFICE.

OSCAR WEIK, OF WAUSAU, WISCONSIN.

CONTAINER.

Application filed February 9, 1928. Serial No. 253,089.

My invention relates to improvements in containers for toothpicks, matches and the like,—the same being an improvement over the container shown in my Patent No. 1,198,980 dated September 19th, 1916.

My prior patent is characterized by a conical upwardly projecting bottom portion which causes the tooth picks to be disposed in upstanding position slantingly with respect to the axis of the container with their upper ends defining an annulus,—the central recess or opening being adapted for insertion of the finger for ready extraction of a single article without handling the others.

In filling a container, manufactured in accordance with my prior patent, it is necessary to tap the upper ends of the toothpicks in order to effect a uniform packing of the same with the upper ends of the articles even. This, in the patented container, resulted in the splitting of a great number of the lower or wider ends of toothpicks. Some lower ends were split by being jammed too forcibly into the wedge-like annular space produced by the intersection of the conical bottom with the side wall of the container. Also the upper ends of the sticks were in many instances broken by reason of the necessity for rather forceful tapping in order to seat the batch of picks or other articles. Toothpicks like any other commodity are sold on the basis of quality, and the breaking of considerable numbers of picks brought forth unfavorable criticism from the trade. Furthermore, in the container disclosed in my prior patent, considerable care was required in order to dispose the picks in the slanting spiral-like formation to define the annulus aforesaid.

It is therefore the primary object of my present invention to overcome the objections afore noted and to provide a container which may be readily filled and the articles disposed in the spiral-like form without the exercise of any considerable care and without the necessity for severe tapping of the upper ends,—thus making it possible to fill the containers in shorter time and without breaking any of the articles.

The foregoing and other objects of the invention are obtained by means of a novel combination and arrangement of parts to be hereinafter described and claimed, reference being had to the accompanying drawing which illustrates the now preferred form of the invention. It is to be understood,

however, that various changes and modifications may be made in the structure shown and described without a departure from the spirit and scope of the invention claimed. 60

In the drawings, wherein the same reference characters have been used to designate the same parts throughout,

Figure 1 is a perspective view of a container constructed in accordance with my 65 invention;

Figure 2 is a group perspective view with the cover removed, and

Figure 3 is a perspective view of the container with one wall portion broken away 70 to disclose the interior formation of the bottom.

Referring specifically to the drawing, the container which is shown circular in cross section, although other forms may be advantageously adapted, comprises a base or holder proper 1 and a top 2, the latter having a depending flange adapted to snugly receive the circular upstanding wall of the base. The base bottom comprises a flat annular portion 4 adjacent the circular outer wall and rising from the intermediate portion of the base is a conical portion 5 which is provided with a plurality of spiral ribs 6 having a common point of origin at the 85 apex of the conical portion 5. As shown the ribs terminate at the inner edge of the annular bottom portion 4.

It is believed to be obvious that when the picks 7 are disposed endwise into the base 90 or body portion 1 the lower ends of the picks will be guided by the ribs 6 in their descent so that the array of picks or other articles will be automatically disposed slantingly with respect to the axis of the container, as shown, whereby their upper ends 95 will define an annulus leaving a central finger hole or recess 8. Thus the articles 7 can be readily removed one at a time without making it necessary to handle any considerable number of the articles in so doing.

The annular base portion 4 serves a very important function in that it provides a flat space of considerable width to receive the lower ends of the picks, so that there 105 will be no possibility of the same jamming and splitting, as is the case in the patented structure due to the restricted wedge-like space into which the lower ends of the picks or articles are jammed.

Manifestly, with the container constructed in accordance with my invention, the

picks can be readily located in place without the necessity for severe tapping of the upper ends which as aforesaid, tends not only to break the upper ends, but also to split the articles at the bottom.

5 In summarizing the advantages of my improved structure it is desired to emphasize that its use will produce a more perfect product; result in easier packing; more 10 speed in packing; the elimination of much of the waste due to broken ends of the article,—and last but not least, the fact that the present container will cost no more than the other container inasmuch as the bottom 15 4, 5 can be molded to define the ribs and outer annular space 4 just as readily as the bottom of the patented container can be produced.

It is to be noted that the circular wall of 20 the base section 1 extends to a point flush with, or above the upper ends of the picks or other articles 7 so that the top 2 can be applied by machinery without injury to the articles.

25 Having thus described my invention, what I claim as new and desire to secure by Letters Patent is:

1. A container for slender articles, such as toothpicks and the like, having a bottom 30 provided with an upstanding conical por-

tion, guide ribs disposed on the surface of said upstanding conical portion for guiding the lower ends of the slender articles outwardly in the direction of the outer wall of the container to a predetermined position. 35

2. A container for slender articles, such as toothpicks and the like, having a flat annular bottom portion adjacent the wall of the container, a conical bottom portion extending from the inner edge of said flat annular portion, and guide ribs on said conical bottom portion for guiding the lower ends of the toothpicks or other articles in a predetermined path toward the flat annular portion of said bottom. 40

3. A container for slender articles, such as toothpicks and the like, having an upstanding conical bottom portion, spiral guide ribs on the surface of said conical portion adapted to engage the lower ends of the slender articles to cause them to assume a spiral formation as they move downwardly and outwardly, thereby providing a recess within the array of toothpicks at the upper ends thereof and disposing the upper 50 ends of the slender articles in the form of an annulus.

In testimony whereof I affix my signature.

OSCAR WEIK.
